UNITED STATES PATENT OFFICE.

JOHN ST. AMAND, OF BROCKTON, MASSACHUSETTS, ASSIGNOR TO WILLIAM B. ARNOLD, OF NORTH ABINGTON, MASSACHUSETTS.

LAST.

SPECIFICATION forming part of Letters Patent No. 731,390, dated June 16, 1903.

Application filed December 31, 1897. Serial No. 664,942. (No model.)

To all whom it may concern:

Be it known that I, JOHN ST. AMAND, a subject of the Queen of Great Britain, residing at Brockton, county of Plymouth, State of Massachusetts, have invented an Improvement in Lasts, of which the following description, in connection with the accompanying drawing, is a specification, like letters on the drawing representing like parts.

10 In the manufacture of shoes, particularly of the finer grades of shoes, the hinged last is rapidly supplanting the old styles of multipart lasts, and in the process of manufacture, as is well known, the lasts are subjected to enormous pressure, at times tending to break or pull out the hinged joint, and therefore requiring that the hinge should be fastened in the last in an extremely secure manner. Accordingly I have invented the construction hereinafter more fully set forth, in which the last is provided with pockets or recesses cut into the solid material thereof, in which is embedded a hinge-like connection which has a positive strong grip into the wood or other material of the last, so that the joint or hinge-like connection cannot pull out endwise without pulling a portion of the last material with it.

In general terms my invention may be said 30 to consist of a last having a heel part and a toe part, each provided with a recess having at a portion of its length within the body or mass of the material an offset extending laterally at a sharp angle from the general direction of the recess, combined with a connecting device for connecting said heel part and toe part together, said device corresponding in general shape to the respective recesses and having one or more laterally-extending 35 portions adjacent each of its ends to extend in and be retained by the offsets prepared therefor.

The details of my invention will be more fully understood in the course of the following description, reference being had to the accompanying drawing, illustrative of one preferred embodiment thereof, and the invention will be defined in the appended claims.

In the drawing I have shown in vertical longitudinal section a last constructed according to and embodying my invention.

The last, which may be of any usual or preferred kind or pattern, is herein shown as one type of multipart last, having a toe part A and heel part B, properly cut away at a 55 in order that the heel part may be turned relatively to the toe part. As herein shown, the heel part and toe part of the last are hinged together at c, the toe part having a recess a', provided with two offsets a² a³, and the heel 60 part having a similar recess b, provided with two opposite offsets b' b². Within these recesses are embedded the opposite ends of a hinge-like connection D, said ends being pivoted together on a pintle d and being herein 65 shown as each comprising leaves d', said leaves having at their ends outwardly-extending portions or flanges d² d³, corresponding in shape to, and filling, the offsets of the recesses, said flanges extending laterally at a 70 sharp angle to the general direction of the connection D, the angles herein shown being right angles, although it will be understood that they might be bent at a more acute angle still, if desired, and also that one of them, 75 either at the top or bottom of either or both ends, might be omitted, in which case, of course, the corresponding offset of the recess or recesses would be omitted.

One main advantage of my invention over 80 the previously proposed constructions of which I am aware is that by having a laterally-extending portion projecting at a sharp angle from the body of the hinge or connection and embedded solidly in the mass of material composing the last a far superior strength and rigidity against longitudinal strain is secured, for the portions d² d³ of the connection grip into the material of the last and cling directly against a solid supporting shoulder thereof, so that before the hinge or other connection can be pulled loose a considerable part of the last itself must be pulled away with it.

In making the last, according to my invention as above described I saw the recesses into the last either partially or wholly across the same or in such other direction as it is desired to place the hinge-like connection, also making a slit-like saw cut or kerf extending perpendicularly of the recess to constitute the offset to receive the flanges or other

lateral projections from the hinge or connection.

Having thus prepared recesses in the respective parts of the last corresponding in shape to the hinge connection which is to be inserted, I irremovably secure or embed the hinge or connection in the last. A snug fit is preferred; but it will be evident that the fit of the hinge in the last may be as tight or loose as desired, this depending upon the cutting of the recesses.

Reduced to its simplest form or elements my invention resides in movably joining the parts of a divided last by a horizontal connection having adjacent one end a transverse flange or projection extending laterally at a sharp angle from the main part of the connection and embedded in the body of the last, it being in practice convenient and advantageous to dispose the connection flatwise horizontally in the last and provide it with a pin-tile or regular hinge at the adjacent faces of the relatively movable parts, as shown, each of the end portions of the connection having one or both of the sharply-bent, flat, or plane flanges embedded in the material of the respective parts of the last, as already described, the wood of the last coming flat against the flange or flanges on both sides thereof.

A last constructed according to my invention offers great resistance to longitudinal strains, the pockets or recesses coöperating with the hinges to provide a positive strong grip, because of the sharp angle, preferably a right angle, which the flanges of the hinge present at their junction with the leaf or leaves composing that part of the hinge and the corresponding shape of the recess in the wood, which abuts and braces against the back side of the flat flange, as well as offering a buttress or resistance-ledge against the flat front face of the said flange. By having a flat parallel-sided offset extending from said recess a portion of its length within the body or mass of the material, said offset extending at a sharp angle from the general direction of the recess, and by having the angle of the flange of the hinge the same and the shape of said flange the same, so as to fit tightly and snugly in said offset, a firm and extremely tenacious grip is secured and wedging action is prevented. The flanges extend from the body or leaves of the hinge at a sharp angle of ninety degrees or less therewith, offering a very powerful resistance to longitudinal strains, the longitudinal pull being thereby distributed over the whole section of the ma-

terial included by the flanges and all the pulling strain coming directly in longitudinal line with the hinge without any lateral movement or splitting tendency.

Having fully described my invention, what I claim as new, and desire to secure by Letters Patent, is—

1. A multipart last, comprising a toe part and a heel part adapted to turn up or pivot on each other, and provided with aligned, horizontal recesses extending longitudinally of the last back in opposite directions from the said pivotal region into the mass of material composing the last parts, and each recess having an offset with parallel flat sides extending laterally therefrom in a plane at a sharp angle to its general direction, and a flexible connection embedded within said toe and heel parts, said connection substantially filling said recesses and having laterally-extending flanges projecting at a sharp angle to the body of the connection into and retained by said offsets.

2. A multipart last, comprising a toe part and a heel part, each provided with a horizontal recess extending from the same point in the meeting faces of said parts back into the respective last part, said recesses terminating at their ends within said last parts each in a narrow slit-like offset extending substantially at right angles to the general length of the recess and on both sides thereof, and a flexible connection embedded within said toe part and heel part, said connection conforming in shape and substantially filling said recesses, and having at its ends pairs of laterally-extending flanges projecting at a sharp angle to the body of the connection into and retained by said offsets.

3. A multipart last having the parts thereof movably joined by a flexible connection permanently secured horizontally in said parts, said connection adjacent one end having a transverse parallel-sided, plane, thin, narrow flange extending laterally therefrom at a sharp angle, and embedded within the material of that part of the last, said material inclosing the same in direct contact therewith at all points, including both sides of said flange.

In testimony whereof I have signed my name to this specification in the presence of two subscribing witnesses.

JOHN ST. AMAND.
